METHOD OF FORMING LABELS

Paul M. Gilfillan, Chicago, Ill., assignor to Shell-mar Products Company, Mount Vernon, Ohio, a corporation of Delaware

Application April 14, 1936, Serial No. 74,305

3 Claims. (Cl. 93—1)

The present invention relates to the production of decorative labels and has particular reference to the provision of an improved type of laminated label having a transparent non-fibrous layer and a backing sheet of paper arranged to overlap itself when the label is assembled with an article to be packaged.

A principal object of the invention is the provision of a method of forming labels of transparent cellulose sheeting and paper laminated together in such a manner that when assembled the labels will present a paper-to-paper overlap.

An additional object of the invention is the provision of a method of forming labels of the type described in which a plurality of the labels are produced in a composite laminated web which subsequently is severed in such a manner as to provide a paper extension on each of the labels.

These and other objects will be evident from a consideration of the following description of the invention and by reference to the accompanying drawing, in which

Fig. 1 is a plan view of a web of label material ready to be cut into individual labels;

Fig. 2 is a cross-sectional view taken along line 2—2 of Fig. 1;

Fig. 3 is a perspective view of an individual label ready to be applied to a package;

Fig. 4 is a perspective view of a round package of candy mints having the label attached thereto, the label being partially broken away to show its method of attachment;

Fig. 5 is a side view of a round metallic can having the label attached thereto;

Fig. 6 is a plan view, on reduced scale, showing an alternative method of forming the labels; and

Fig. 7 is a fragmentary view showing a second modification of the label.

For a number of years the practice has grown of applying to packages of various types an outer wrapping of transparent cellulose sheeting such as regenerated cellulose and cellulose acetate. These materials are characterized by their non-fibrous structure and a particular problem which has been met with in the production of packages having an outer transparent cellulose sheeting wrapper is the production of a satisfactory closure. Due to the non-fibrous character of the cellulose sheeting it is difficult to obtain a glue which will produce a satisfactory bond between overlapped edges of the sheeting.

This problem is met with in particular in the case of labels, as in can labels, where the transparent cellulose sheeting is wrapped tightly about

the round can in the usual manner and the overlapped edges of the label are glued together.

As shown in Figs. 4 and 5, my improved label is applied to form a package in which the ends of the transparent cellulose sheeting are not adhesively secured together. In producing the improved label a web 10 of transparent cellulose sheeting is adhesively secured substantially throughout its entire area to a backing sheet or web 11 composed of a fibrous material such as paper. The paper backing member has an attaching portion 12 extending beyond the edge of the cellulose sheeting, as shown in Fig. 3. By combining the cellulose sheeting to a fibrous material substantially throughout the coextensive area of the two webs, the cellulose sheeting is firmly anchored, even though it is of a non-fibrous character. The labels then are wrapped about the package to which it is desired to apply them, in such a manner that the paper adjacent the end of the laminated web opposite the strip 12 overlaps the latter in the manner shown in Fig. 4. The fibrous paper is of such nature that it will hold the label in position about the container in a firm manner, even when the label is applied with a wet glue. It will be noted that the cellulose sheeting does not bear any of the strains incident to holding the label in place. As shown in Fig. 4, the label is wrapped about a rigid package 13 of candy mints which initially are wrapped in some material such as waxed paper or foil, the label forming a jacket about the package of mints.

As the principal purpose of the label is to bear advertising matter and a description of the goods contained within the package, it is desirable to apply printed matter interiorly of the two webs. That is, the printed matter is applied in reverse to the inner face of the transparent cellulose sheeting and the sheeting thereafter is adhesively secured to the web of paper substantially throughout the coextensive area of the two webs.

In production, it is desirable to manufacture the labels in quantities and for this purpose a plurality of the labels are shown in Fig. 1 as being formed from webs of paper and cellulose sheeting. The paper web 11 extends beyond the web 10 of transparent cellulose sheeting on both sides and the two webs are adhesively united together after the printing operation to produce a composite material. Thereafter, the composite web is cut in the manner shown in dotted lines on Fig. 1 to produce individual labels of the type as shown in Fig. 3. It is preferred to laminate the paper and cellulose sheeting webs together in the

- same operation with the printing and to employ a lacquer ink deposited by an etched intaglio cylinder as the bonding material between the two webs.
- 5   In the embodiment of the invention shown in Fig. 6, webs of substantially twice the width as the webs shown in Fig. 1 are secured together by an intaglio printing unit in which an etched cylinder deposits the lacquer bonding material to 10 the entire surface of the transparent cellulose sheeting except for a central strip 14. The paper has edge portions 12 extending from the outer edges of the transparent cellulose sheeting and after lamination of the two sheets together the 15 central strip 14 which is not adhesively secured to the paper backing member is removed as by being slit along lines 15 and 16. After removal of the strip 14 the composite web is cut in the manner indicated by the dotted lines in 20 Fig. 6. It will be noted that the web 6 has four labels across its face. By duplicating the operation by which the strip 14 is produced and removed, the width of the web may be such as to produce six or more labels.
- 25   In the embodiment of the invention shown in Fig. 7, the transparent cellulose sheeting and paper webs are coextensive and there is provided on the outside surface of the paper along one edge of the label a second paper attaching strip 30 17. It will be observed that in this embodiment the opposed edges of the paper web 11 are glued respectively to opposed edges of the attaching strip 17. That is, the transparent cellulose label is provided with a paper carrier adhesively secured thereto along substantially its entire area and opposite edges of the paper carrier are bonded to a common strip of paper. As before stated, 35 the paper itself is of such nature as to be glued together with ease. In some instances it will be 40 found possible to eliminate the strip 17.

Various changes in the structure as described herein for purposes of illustration and explanation are possible without departing from the scope of the invention as defined by the appended claims.

5

I claim:

1. The method which comprises adhesively securing the printed side of a web of transparent cellulose sheeting having printed thereon a series of at least four label units to a fibrous web of 10 paper having edges extending beyond the transparent cellulose sheeting, said securement being substantially continuous except for an unglued longitudinally extending central strip, severing the unglued central strip from the transparent 15 cellulose sheeting, and cutting the combined web into at least four series of labels including a longitudinal cut along the unglued central strip.
2. The method of forming labels, which comprises adhesively securing the printed side of an 20 overall printed web of transparent non-fibrous sheeting substantially throughout its area to a fibrous web of paper having at least one edge extending beyond the transparent sheeting to provide a glue flap, and cutting the resulting 25 composite web into individual labels having a paper edge extending beyond the non-fibrous transparent sheeting.
3. The method of forming labels, which comprises adhesively securing the printed side of an 30 overall printed web of transparent non-fibrous cellulose sheeting substantially throughout its area to a fibrous web of paper having edges extending on each side thereof, and cutting the 35 resulting composite web into individual labels having a paper edge extending beyond the non-fibrous cellulose sheeting to provide a glue flap.
